Primary Examiner — Keli L Hill*Assistant Examiner* — Karra S Johnson(74) *Attorney, Agent, or Firm* — Plumsea Law Group, LLC(57) **CLAIM**

The ornamental design for a public announcement system, as shown and described.

DESCRIPTION

FIG. 1 is a perspective view of a public announcement system showing our new design;

FIG. 2 is a front elevational view thereof, the rear elevational view being a mirror image thereof;

FIG. 3 is a side elevational view thereof, the opposite side elevational view being a mirror image thereof;

FIG. 4 is a top plan view thereof; and,

FIG. 5 is a bottom plan view thereof.

The broken lines shown are included for the purpose of illustrating portions of the public announcement system that form no part of the claimed design.

1 Claim, 5 Drawing Sheets(56)
